UNITED STATES PATENT OFFICE.

WILLIAM J. EGAN AND JOHN J. O'BRIEN, OF ST. LOUIS, MISSOURI.

CABLE-GRIP.

SPECIFICATION forming part of Letters Patent No. 427,756, dated May 13, 1890.

Application filed April 6, 1889. Serial No. 306,281. (No model.)

To all whom it may concern:

Be it known that we, WILLIAM J. EGAN and JOHN J. O'BRIEN, both citizens of the United States, residing at the city of St. Louis, State 5 of Missouri, have jointly invented certain new and useful Improvements in Cable-Grips for Railways, of which the following is a specification.

Our invention relates to that class of rail-
ways wherein the cars or coaches receive their
motion from an endless cable which passes
from a power-house through a tunnel or con-
duit located below the road-bed or railway-
track, such motion being imparted to the cars
10 by means of a gripping-machine located on
the grip-car. In operating such cable rail-
ways it frequently becomes necessary to make
crossings where one road intersects or crosses
another, the cable of each respective road pass-
ing at such points above or below each other,
thus making it desirable to have the grip of
the road operating the lower cable at any
such point of intersection or crossing made
so that it will be capable of wholly releasing
25 the lower cable, and at the same time be al-
lowed to pass wholly over the upper one and
at a safe distance from both, and, when the
crossing is effected by the momentum of the
car previous to releasing the cable, be sus-
20 ceptible of again being lowered, so as to grasp
and manipulate the cable to continue travel;
and the object of our invention is, first, to pro-
vide a cable-grip that will accomplish said
ends; second, to dispense with the necessity for
25 using "gypsies," so called, or other auxiliary
machines or devices at such crossings to en-
able a car to resume its journey by regripping
the cable; third, to provide means whereby
the cable-grips may be wholly raised over the
30 cable or cables while running and conven-
iently dropped into a position for again gripp-
ing and operating it. We attain these ob-
jects by the mechanism illustrated in the ac-
companying drawings, in which—
35 Figure 1 is a side elevation of our improved
cable-grip, showing the same in position upon
the grip-car and having its jaws fastened upon
the cable in the conduit. Fig. 2 is an end
view of the same. Fig. 3 is a view in cross-
40 section on line 3 3, Fig. 1; Fig. 4, a side eleva-
tion showing the upper jaws in position to
receive the lower jaws and cable after a cross-

ing has been effected. Fig. 5 is a top sectional
view of lower jaws on line 5 5, Fig. 4. Fig. 6
is a view in cross-section on line 6 6, Fig. 4; 55
and Fig. 7 is a view of the lower die-plate.

A represents the cable-conduit; B, the main
lever; C, a flat segmental bar provided at its
upper periphery with a toothed rack having
the teeth running in opposite directions from 60
sides to center, which enables the operator to
work from either side.

D is a cross-head, preferably in the form of
a flat steel top bar, connecting the perpen-
dicular bars g g, and which works in the slot 65
formed by the inner vertical surfaces of the
fixed bars F F.

E is a cam or eccentric centered at e for
operating the middle upright G and lower
gripping parts O O between the fulerums or 70
lugs L L by the lever arm or handle e'. The
lugs L L are stationary on the cross-head D,
and the cam or eccentric E has lateral and
perpendicular motion in the slot, as shown in
dotted lines at E', Figs. 1 and 4, where it is 75
fitted on bolt and washer connection, for the
purpose of operating the parts G g g and lower
jaws H. The bar G is provided at its lower
end with an egg-shaped plunger N, which op-
erates in the socket n, formed by the two in- 80
sides of the projections h of the lower grip-
ping-jaws H, which are adapted to receive it
and which open and close said jaws upon the
cable by the up-and-down movement of the
bar G and plunger N. The main lever B is 85
pivoted on the lateral connecting-bar J in the
middle of the grip, and is provided with a link
b³, pivoted to the lever B and cross-piece D
at points b⁴ b⁴. (See Fig. 4.)

To the lower end of the bars g g are hinged 90
the lower jaws H by the hinge-and-bolt con-
nections h' h'.

O O are the lower die-plates, which are seated
in the jaws H and secured by bolts and nuts.
The jaws H are made so as to overlap one 95
another, as shown at h², Fig. 2, thus forming a
continuous bearing for the cable M to run in.
The uprights F F at their lower ends carry
the upper gripping-jaws f f, the latter being
grooved at their lower ends to receive the 100
cable.

f' is a flat bar connecting the lower part
of the uprights F F.

K K represent the floor of the grip-car.

The cable being released from the gripping jaws, as shown in Figs. 4 and 6, when the grip-car is approaching a crossing or intersecting line of cable the plunger-bar G is first lowered by slightly moving handle e' of cam or eccentric E to force open the hinged jaws H H, as shown in Figs. 4 and 6. The main lever B is then disengaged from the segment c and thrown forward to release the grip from the cable, and the cam-lever E is then moved by a downward motion of its bar e' to raise the parts g g and G, with the open jaws H H, sufficiently high to allow the entire grip to safely pass over the intersecting cables in the conduit at the crossings. When this is accomplished, the lever e of cam E is thrown upward to position shown in Fig. 4 to close the jaws H H fully, and the lever B is then moved into the position shown in Fig. 1 to cause said jaws H H to engage the cable with the upper jaws f f on the bars F F.

What we claim is—

1. In a cable-gripping device, the combination of a stationary frame having jaws f f, a cross-head D, having the bar G and bars g g, with hinged or pivoted jaws H H at their lower

ends, and the plunger N, engaging with the upper ends of said jaws H H, and actuating devices for said plunger, and separate actuating devices for said cross-head and bars g g, substantially as shown and described. 30

2. In a cable-grip, the combination of the plunger N, the hinged jaws H H, having a socket n, actuating devices for said plunger, whereby the jaws H H are opened and closed, 35 and separate actuating devices for raising and lowering said jaws, substantially as shown and described.

3. In a cable-gripping device, the combination of a movable yoke having hinged gripping-jaws, a fixed frame having stationary jaws, a slot in the upper end of said fixed frame in which said yoke moves, and actuating devices for opening and closing the movable jaws and for raising and lowering them, 45 all substantially as shown and described. 40
